UNITED STATES PATENT OFFICE.

ERNEST FRIEDHEIM, OF PARIS, FRANCE.

DEVICE FOR MANUFACTURING MOLDS.

No. 906,007.

Specification of Letters Patent.

Patented Dec. 8, 1908.

Application filed October 29, 1907. Serial No. 399,709.

To all whom it may concern:

Be it known that I, ERNEST FRIEDHEIM, a subject of Great Britain, residing at Paris, France, have invented a new and useful Device for Manufacturing Molds Used in the Electrolytic Methods of Making so-called Honeycomb Radiators, for which I have obtained a patent in France, No. 371,829, bearing date November 27, 1906; and I do hereby

10 declare the following to be a full, clear, and exact description of the same.

The present invention has for its object a device for manufacturing molds used in the electrolytic methods of making so-called honeycomb radiators. In producing these radiators electrolytically, a mold or core of fusible alloy is used upon which the metal, for instance, copper or the like, constituting the radiator, is deposited electrolytically.

15 The process of manufacture of molds in using the device established, consists in casting metal fusible at a low temperature around mandrels of suitable form placed vertically one beside the other with their 20 points of contact at their base upon a slab capable of being heated. These mandrels of any geometrical form whatever are preferably in the form of truncated pyramids of a hexagonal section and are provided at their 25 bases with hexagonal parts from 15 to 20 mm. in height slightly projecting beyond the body of the mandrel, which projection will constitute the space of the mold the thickness of the walls of the casting thus depending 30 upon the projection (in practice 2/10ths to 10/10ths m.). The bottom of the mold is thus constituted by the mandrels themselves, the slab upon which they are placed simply providing a plane surface. These mandrels or 35 pins which necessarily have the form that it is desired to give to the spaces of the casting and consequently to the radiator to be formed, must be slightly tapered upon the part about which the fusible alloy will be 40 cast, in order to facilitate the removal of the casting. The prismatic part at the base of each mandrel enables the mandrels to be rigidly and accurately secured in a true vertical position by means of simple wedging 45 in a steel frame. Each of the mandrels is, on the other hand, furnished at the upper extremity with a conical portion upon which pressure can be exerted to effect removal of the mandrels from the casting. The upper 50 ends of the mandrels may receive a perforated plate which may keep all the mandrels

in the correct relative position in case of any tendency of the latter being displaced.

The accompanying drawing illustrates by way of example and in elevation part of a 60 mold constructed as hereinafter described.

a designates the mandrels of any geometrical section whatever but slightly tapered to permit removal from the casting. *b*, designates their hexagonal prismatic bases. *c*, 65 the slab upon which the mandrels are placed and *d* the upper conical portion of each mandrel.

In carrying out the process in practice the following operation is adopted:—Upon 70 the slab, *c*, placed upon any heating hearth whatever and slightly inclined as desired, a steel frame *e*, is disposed, the frame having the height of the lower prismatic parts of the mandrels this frame being itself surrounded by a false frame of plate iron, *f*, having a height equal to that part of the mandrels which constitutes the core for the casting the frame being pressed upon the slab, for instance, by the aid of screwed 80 gudgeons or by bars of steel, *g*, furnished with clamps and rendered liquid-tight by means of a joint of asbestos or other means. At the upper part of the false frame one or more reglets are temporarily provided to 85 hold the above described mandrels in an absolutely vertical position when the slab, *c*, is horizontal. The steel frame, *e*, may be preferably formed from one piece of metal whereas the false frame of sheet or plate 90 iron, *f*, may be constituted by two pieces placed at right angles. It therefore suffices to place the mandrels, *a*, one after the other in position, the hexagonal form of their bases and the temporary inclination of the slab 95 holding them together in place. The steel frame, *e*, must be so calculated as to contain a certain number of mandrels and so as to permit no lateral play between them.

Once all the mandrels constituting the 100 mold have been placed in the steel frame which remains surrounded by the false frame pressed against the slab, the latter may be placed in a horizontal position and then after being heated to the necessary 105 temperature to obtain a good casting the metal is poured in from above. As soon as the metal is set the false frame is removed and the casting thus made is lifted by means of hooks which have been previously placed 110 in the molten mass, the mandrels being driven out by means of a mallet or of a press

as well as the steel frame which will remain adhering thereto, a cast honeycomb in fusible metal being thus obtained. The mandrel and the frame falling back into the place which they have occupied, it is only necessary to replace the false sheet iron or plate frame to effect a fresh casting. The arrangement permits of the mold being varied as much in height as in surface simply by the aid of a number of frames and false frames of different dimensions each substituted according to the number of mandrels that it is desired to employ.

I claim:

15 A device for the manufacture of molds for honeycomb radiators, said device comprising mandrels each having a prismatic hexagonal base cast around the same, the juxta-

position of said bases constituting the bottom of the receptacle into which the fusible metal is cast, a table, a steel frame inclosing said base, sheet metal walls constituting the sides of the mold, locking rods which lock said walls on the table and on the base of the mandrels, and movable gages to determine the vertical position of said walls and their distance from each other in respect of the mandrels.

In testimony whereof, I have signed my name to this specification in the presence of two subscribing witnesses.

ERNEST FRIEDHEIM.
